UNITED STATES PATENT OFFICE

JOHN WILLIAM TERNAU, OF GLOUCESTER CITY, NEW JERSEY, ASSIGNOR TO HERMAN H. TERNAU, OF NEW LONDON, CONNECTICUT

FURNACE ATTACHMENT

Application filed December 14, 1929. Serial No. 414,025.

This invention relates to improvements in fuel burners for use in furnaces or the like to increase the combustion of the fuel and heating capacity of the furnace, and in raising steam in stationary, marine and other boilers by an attachment thereto as for instance described in my Patent No. 1,746,061, dated February 4th, 1930, of which this application is a continuation in part.

10 It is the principal object of this invention to provide a cone shaped furnace or boiler attachment equipped with a plurality of deflector vanes of a new and improved construction constituting means to present resistance to the air forced through the cone casing by the motor driven multi- or 8 blade aeroplane type fan at a point before the air reaches the deflector vanes, and thereby creating an air pressure within the cone casing constituting the means for building up air cross currents through the center deflector ring and deflector vanes. The cone casing is so formed at the large end where the fan is attached to cause a free discharge 25 of air into the same and provide means for the fan to cause a suction on the outside and producing an air pressure within the cone casing.

Thus a maximum of heat by a minimum 20 consumption of fuel, such as for instance oil under pressure, forced through a burner, is produced, by mixing the fuel with air under pressure produced by the motor driven aeroplane type fan.

35 Another object of my invention is the provision of a furnace attachment of the above type of comparatively simple construction yet durable and efficient in its operation for the purpose in view, an attachment which 40 will greatly reduce the cost of repairing and of replacements for worn parts, as each part of the attachment is interchangeable and portable.

Still another object of my invention is 45 the provision of a furnace or boiler attachment adapted to be readily attached to any size of furnaces or boilers of the conventional constructions, without the necessity of materially changing the furnace or boiler construction, and in which the air and fuel are

imparted a whirling motion ensuring a nearly perfect combustion.

A further object of my invention is the provision of a furnace or boiler attachment equipped with a regulator shutter plate provided with openings and movable shutter sections enabling the use of the attachment on a furnace or boiler, operated in a closed compartment or fireroom under constant air pressure.

60 A still further object of my invention is the provision of a furnace or boiler attachment equipped with a center deflector ring for the purpose of forming a cross-current of air, and changing the angle of oil film spray deflection to a lesser or greater degree, as desired, thereby also imparting a whirling motion to the air and oil film spray.

The invention includes also the provision of a drip trough formed with the center deflector ring or body and means for guiding the drip oil to prevent the combustion of the same and the formation of dangerous gases.

75 It is also the object of the present invention to provide a safety screen for the fan which is preferably of the multi-vane or blade type and constructed for producing air pressure and adapted to be operated with variations in speed so as to produce the necessary quantity of air required and in 80 proportional relation to the amount of fuel oil to be burned. The fan is of the multi- or 8 blade airplane type with set pitch of blades and clearance to produce air pressure 85 in a conical casing and having said air pressure develop force of motion for the additional deflection of cross-currents and revolving motion.

90 These and other objects and advantages of my invention will become more fully known as the description thereof proceeds and will then be specifically defined in the appended claims.

95 In the accompanying drawings forming a material part of this disclosure:

Fig. 1 is a sectional side elevation of the boiler or furnace attachment, constructed according to my invention.

100 Fig. 2 illustrates the outside lever arrange-

ment for moving the center deflector ring in front and side elevation.

Fig. 3 is a top plan view of the shutter plate.

5 Fig. 4 is a top plan view of the motor support.

Fig. 5 is a top plan view of the center deflector ring and deflector vanes of the cone casing.

10 Figs. 6 and 7 are detail views illustrating the construction of the upper rim of the casing.

Figs. 8 and 9 illustrate the screen in top plan view and side elevation respectively.

15 Fig. 10 is a top plan view of the center deflector ring.

Fig. 11 is a section on line 11—11 of Figure 10.

20 As illustrated, my improved and novel furnace attachment comprises a substantially cone-shaped casing or casting 10 having an end flange 11 by means of which the device is adapted to be attached to a furnace or boiler front indicated at 12.

25 At an appropriate place the casing 10 is provided with a lighting off hole 13 equipped with a movable cover 14.

30 A shutter plate 15 having a handle 16 formed therewith is portable and can be suitably attached at the large end of the casing

35 10 as for instance by inserting it between an angle ring 46 and the large end of cone casing 10, and has formed therewith a substantially V-shaped ring 18 adapted to engage a similarly shaped depression or groove in an asbestos packing 19 embedded in the large end of the casing 10 of the furnace attachment.

40 A bracket 20 is attached on the three lugs 22 inside of casing 10.

45 A yoke 23 constituting a holder for an oil burner body 24, and parts associated therewith, has at its inner apex a perforated boss 25 which is equipped with inner thread allowing the passage of a screw bolt 26 which carries at its outer end a hand wheel 27, while its inner pointed end engages the burner body 24.

50 To the inner end of the yoke a two armed bracket 28 is secured by means of bolts and nuts 29 carrying suitable washers, while the outer ends of the bracket arms are slotted, as at 30, to allow the securing of the yoke and burner therein to the bracket 20 by means

55 of screws 31 carrying wing nuts 32 and encased in oil tight copper packing ring 33 so that the burner and its holder yoke can easily be taken apart and removed as a complete unit from the interior of casing 10 of the attachment.

60 The oil is supplied under pressure to the burner body by means of the oil supply pipe 34 and is fed to a pipe 36 equipped at its furnace end with a nozzle or tip of conventional

type, as for instance described and shown in my above cited patent.

Deflector vanes or baffle plates 41 are arranged at the rear part of the attachment to ensure a suitable distribution of the air.

70 The air is forced into the attachment's casing 10 by means of a fan arrangement comprising a motor 42 attached to the casing by means of a bracket 43 and having its shaft 44 equipped with a multi-blade airplane type 75 fan 45, a screen 46 protects the operator from getting his clothing or parts of his body caught in the fan, during operation of the attachment, and is arranged as will hereafter be more fully described.

80 In order to form a cross-current of air and for the purpose of changing the angle of oil film spray deflection to a lesser or greater degree, as desired, I provide the following mechanism:

85 A center deflector ring 56 is supported by guide bars 50 depending from bracket 20 carrying intermediate their ends bosses 49 secured to bar 50 by means of dowel pins 51. Internal operating levers 48 are pivotally set 90 at their bottom ends, as at 48' between bosses 51 while their upper ends are secured to an operating shaft 52 by means of dowel pins 55 which is movably arranged in bearing bosses 47.

95 The center deflector ring 56 has formed integrally therewith three rings 57, 58 and 59 of different diameters and of predetermined angles and shape, and the estimated set position of each ring ahead of each other relative to the increase of diameter is operative 100 in order to ensure the proper courses of the air currents to form the required spray angle and for imparting to the air and oil film spray its proper whirling motion. The rings 57, 58, and 59 as part of the center deflector ring are properly guided in guides 60, 61, 62 and 63 (Fig. 5) while bosses 64 as part of the center deflector ring receives the threaded ends of the guide bars 50.

110 Figure 2 illustrates the construction and arrangement of the outer lever and co-operating parts. The shaft 52 of the inner operating lever 48 carries outside of casing 10 a lever 66 similar to inner lever 48 pivotally 115 connected at its outer end, as at 65 to an operating lever 69 adjustably guided in an angle clip 70, and provided with a lower end handle 71.

120 Figure 3 illustrates in detail view the shutter plate 15 with its handle 16 composed of an upper or outer plate 72 and an inner or lower plate 73. The outer plate has curved peripheral slots 74 formed therein in which 125 are guided buttons 75 of the inner plate to allow an adjustment of the shutters 76 to vary the size of the slots between them. Shutter plate 15 has on its outer periphery three extensions and three spaces are pro- 130

vided therein for centering the shutter plate between angle ring 46 and casing 10.

An oil overflow receiving vessel is designated 71' in Figures 1 and 11. The trough arrangement 71' is casted with and forms part of the movable center deflector ring 56 and provides means for collecting dripping oil when the burner is not in operation and in the event that the valve controlling the oil flow to the burner is not properly closed or leaks. Thus this trough and the pipe 84 leading therefrom to the outlet nozzle 86 constitutes a safety device preventing the leak oil from entering the furnace unburned, and also from leaking down between the brickwork of the furnace wall and furnace casing which will eliminate the danger of combustible gases being formed in other places than the furnace combustion chamber. Figures 6 and 7 illustrate the construction of the upper rim or margin of receptacle or casing 10.

As shown in these figures, the angle ring 46 forms the means of support of brackets 43, motor 42 and fan 45 and is held in closed position by a spring snap lock 67 engaging a shoulder or block attached to the outside of casing 10. Pivot 72 allows swinging of the angle ring on the opposite side of the casing 10.

As shown in these figures the inner faces of the upper rim of casing 10 are stream-line as shown in Figures 1, 6, and 7 in order to cause or allow a free discharge of air into the cone casing so as to provide means for allowing the fan to cause a suction on the outside of the casing and to produce an air pressure within the cone casing.

The operation of my attachment will be clearly understood from the above description on hand of the accompanying drawings, and it will be clear that the arrangement of the protecting screen for the fan will prevent injury to the operator while the screen attached to the angle ring 46 may easily be swung about its pivot 46' after release of the catch to give access to the motor and shaft for lubrication, clearing and repairs.

The stream-line form of the upper cone casing margin will allow a free discharge of air into the casing and cause a suction on the outside for producing an air pressure within the casing.

The center deflector ring 56 with its three auxiliary deflector rings or vanes, of different diameters will receive the air under pressure for the purpose of producing cross-currents of air and for changing thereby the angle of oil film spray deflection to a lesser or greater degree as desired, and effected by the proper adjustment of the angle of the pivoted lever or levers 48, 66, by means of the outer operating lever effecting a moving of the center deflector ring inwardly or outwardly and thereby causing a change in the

angle of air cross-currents and thus changing also the angle of the oil film spray deflected to a lesser or greater degree as desired.

The multiblade fan of the aeroplane propeller type with set pitch of blades is especially well adapted to produce the required amount of pressure within the attachment casing for deflection by the deflector vanes after they have been properly adjusted as above outlined so as to produce currents and cross-currents for the proper mixture of air and oil and deflecting the spray as desired.

It will be understood that I have described and shown the preferred form of my invention as an example only of the many possible ways to practically construct my invention, and that I may make such changes in the general arrangement thereof and in the construction of the minor details of my invention without departure from the spirit of my invention and the principles involved.

Having thus described my invention, what I claim as new and desire to secure by Letters Patent is:

1. In a furnace or boiler attachment of the class described, a frusto-conically shaped casing open at one end, a motor operated fan on the open end of said casing, the opposite end adapted to be attached to a furnace or boiler, a protecting screen for said fan, a hinge for allowing an opening of said fan screen to give access to said fan, a snap-lock for holding the screen casing closed over said fan to protect the operator against injury, a plurality of air deflector vanes, and means for raising and lowering said deflector vanes.

2. In a furnace or boiler attachment of the class described, a frusto-conically shaped casing, a means for furnishing air under pressure to said casing, a regulator shutter plate formed with openings and shutters closing the same allowing the regulation of the shutters and openings to the desired width for regulating the amount of air furnished to said casing and a plurality of air deflector vanes, and means for raising and lowering said deflector vanes.

3. In a furnace or boiler attachment, a substantially frusto-conically shaped casing adapted to be secured to an oil fired furnace or boiler, a center deflector ring in said casing, a means for suspending said deflector ring within said casing, a plurality of auxiliary deflector rings of varying diameters formed integrally with said center ring, guides for said deflector rings, means for allowing an adjustment of the said deflector rings, and means for effecting this adjustment from the outside of the casing said latter means comprising a pair of bosses on said suspending means in spaced relation, inner operating levers pivoted at one end and engaged in the space between said bosses, and outer levers for turning said inner levers about their pivot points.

4. In a furnace or boiler attachment of the class described, a plurality of deflector vanes, rods for suspending said vanes within said casing, bosses on said rods, an inner operating lever pivotally engaging said rods between said bosses, a shaft for said lever, an outer similar lever on said shaft, and an operating lever on the outside of the casing for operating said inner pivoted levers to raise and lower said deflector vanes and to hold the same in any of their adjusted positions.
5. In a furnace or boiler attachment, a frusto-conically shaped casing, means in said casing for forming a cross-current of air and for changing the angle of an oil film spray, said means comprising a center deflector ring, a plurality of rings of different diameters and predetermined angles and shapes integrally made with said center ring, guides for guiding said rings, a guide bar for the center ring, bosses on said guide bar spaced from one another, inner operating levers having inner headed ends set in the space between said bosses, a shaft to which the other ends of said inner operating levers are secured, an outer lever arm secured at one end to said shaft, and an outer operating lever pivotally attached at its upper end to the opposite end of said outer lever arm for adjusting the position of said deflecting rings to produce the desired deflection of air and oil film.

Signed at Gloucester City, in the county of Camden and State of New Jersey, this twenty second day of November, A. D. 1929.

JOHN WILLIAM TERNAU.
